(57) CLAIM

The ornamental design for an inflatable towable vehicle, as shown and described.

DESCRIPTION

FIG. 1 is a perspective view of the inflatable towable vehicle showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines shown in FIGS. 1 and 4 are for illustrative purposes only and do not form part of the claimed design.
